STITCHDOWN SHOE AND METHOD OF
MANUFACTURE

Eckard F. Schmidt, Milwaukee, Wis., assignor to
United Shoe Machinery Corporation, Paterson,
N. J., a corporation of New Jersey

Application October 16, 1934, Serial No. 748,509

9 Claims. (Cl. 12—142)

This invention relates to a shoe and a method of making it, and more particularly to a stitchdown shoe containing a toe stiffener which has no outturned flange, and to a method of making such a shoe.

In stitchdown shoes, it is common to form an outturned flange on the upper as well as upon the toe stiffener, and to fasten these outturned flanges to the extension innersole by stitches or staples. The presence of the outturned flange of the toe stiffener, which is commonly made of fabric impregnated with a stiffening substance, is objectionable since it interferes more or less with the production of a nicely finished sole edge on the completed shoe. According to the present invention, a stitchdown shoe is provided in which the toe stiffener has no outturned flange.

According to a method commonly used in manufacturing stitchdown shoes, after certain operations have been performed, there results an assembled upper mounted, together with an extension innersole, upon a last, a softened toe stiffener having been inserted between the toe portions of the upper and the lining. The toe portion of the shoe is then presented to a toe-forming machine the function of which is to impart to the toe portion of the upper and to the toe stiffener a form corresponding to that of the toe end of the last, and to make a portion of the upper into an outturned flange which overlies the margin of the extension innersole. After shoes have been thus operated upon, they are presented to a stitchdown lasting machine by which the upper is further formed and its outturned flange, including that at the toe portion, is fastened to the extension innersole, for example by stitches.

In producing the shoe of the present invention, a short toe stiffener upon which no outturned flange is formed is employed; and when such a toe stiffener, previously rendered soft and limp, has been put in place, and shaped, for example by means of the toe-forming machine, it is desirable that it be held so that its molded shape will be maintained approximately unchanged until the outturned flange of the upper is permanently fastened to the extension innersole, for example by means of the stitchdown lasting machine. This procedure is particularly well suited for use with toe stiffeners of the type of those which are treated with a liquid to render them soft. As examples of toe stiffeners of this type, there may be mentioned those made of fabric impregnated with celluloid which are treated with a solvent for the celluloid and thus

rendered soft and limp before being put in place, and those which are rendered soft and limp by treatment with water. In both cases the liquid must evaporate before the toe stiffener sets in its molded shape. In order to maintain the toe stiffener in its molded shape after it has been molded and prior to the permanent attaching of the outturned flange of the upper to the extension innersole, this outturned flange is temporarily fastened to the margin of the extension innersole, preferably by cement, so that the toe stiffener is confined and prevented from losing its shape.

Referring to the accompanying drawing,

Fig. 1 is a cross section of the toe portion of a three-sole stitchdown shoe, and of a portion of a toe-forming machine showing the parts of the shoe and of the machine as they appear at the end of the toe-forming operation;

Fig. 2 is a plan of a part of the extension innersole of the shoe shown in Fig. 1, said innersole having a coat of cement across its toe portion;

Fig. 3 is a cross section of the toe portion of a finished three-sole stitchdown shoe;

Fig. 4 is a cross section of the toe portion of a finished two-sole stitchdown shoe; and

Fig. 5 is a plan of a part of the extension innersole of the shoe shown in Fig. 4, said innersole having a stripe of cement extending along the margin of its toe portion.

Referring first to Figs. 1, 2 and 3, the shoe therein shown may be made as follows. An insole 1 is tacked to the bottom of a last 9. A coating of cement is applied to the lower margin of the inside of the lining 11 of the assembled upper, a portion of the upper proper being shown at 13. The assembled upper is then mounted on the last as usual, tacked to the heel end of the last and pulled-over including the driving of the usual pulling-over tacks. A coat of cement is applied to the margin of the under face of the insole 1 just wide enough to allow for lasting the lining. After the cement has dried sufficiently, the lower margin of the lining is lasted-over upon the margin of the insole. The heel seat is then lasted, although this operation may be performed before the lasting of the lining, if desired. The pulling-over tacks are removed, and an extension innersole 15 is tacked to the last, said extension innersole having been previously coated with cement 17, preferably a thermoplastic cement, which has been allowed to set. At this point, the toe portion of the upper is raised and a short toe stiffener 19—that is one on which no outturned flange is to be formed—

which may be limp by reason of the presence of a liquid, is put in place, and a narrow extent of its lower margin is folded-in under the lasted margin of the lining, the width of the folded-in margin being in the neighborhood of one-eighth of an inch. The thermoplastic cement on the extension innersole 15 is then softened by heat, for example by placing the toe portion of the shoe in a toe-softening machine, after which the toe portion of the shoe is formed, for example by the use of a toe-forming machine, such as that disclosed in United States Letters Patent No. 1,861,832, granted on April 7, 1932, upon an application filed in the name of William C. Baxter. This machine is provided with a holddown 21, wipers 23 and a work support 25, these parts being shown in Fig. 1 in the positions they occupy after the wipers have drawn the upper, together with the toe stiffener, about the toe portion of the last, and a part of the upper has been formed into an outturned flange and pressed against the margin of the cemented face of the extension innersole 15. When, therefore, the shoe is removed from the toe-forming machine, the outturned flange adheres to the extension innersole and confines the soft toe stiffener 19 so as to hold it substantially in its molded shape. This cement joint is a temporary fastening to hold the stiffener properly until the shoe is lasted and the outturned flange of the upper is permanently attached to the extension innersole. The lasting and permanent attaching may be done, for example, by means of a stitchdown lasting machine, such as that disclosed in United States Letters Patent No. 1,864,510, granted on June 21, 1932, upon an application filed in the name of Bernard T. Leveque, which lasts the shoe and fastens the outturned flange to the extension innersole by stitches, as indicated at 27 in Fig. 3. The shoe may now be finished in the usual manner, including the attaching of the welt 29 and the outsole 31 by the usual stitches 33. It will be noted that in the manufacture of this three-sole shoe the wearer's foot does not contact with the extension innersole 15 and, consequently, that said extension innersole may be coated all the way across, as shown in Fig. 2, which simplifies the cementing operation. It should also be noted that thermoplastic cement, which is liable to be squeezed out more or less during the toe-forming operation, may safely be used since none of the squeezed-out cement will cause any sticking of the shoe to the last during its manufacture.

The two-sole shoe shown in Figs. 4 and 5, which has no insole like the insole 7 of the three-sole shoe, may be made as follows. A heel seat piece is tacked to the last; and the assembled upper, including the upper proper 113 and the lining 111, is mounted on the last. The assembled upper is pulled-over, the pulling-over tacks being driven into the bottom of the last. The heel seat is lasted to the heel seat piece. The pulling-over tacks are removed, and an extension innersole 115, which has been coated along its margin with a stripe of cement 117 of proper width, is tacked to the last. Preferably, a cold process cement, for example rubber cement, is used since, if thermoplastic cement is used, some of it is liable to be squeezed out during the subsequent toe-forming operation, thereby causing the shoe to stick to the last. The shoe is now ready for the insertion of the toe stiffener 119. In the better grade of shoes, the toe portion of the upper is laid back, and the toe portion of

the lining is formed, for example by the use of the toe-forming machine. Cement is applied either to the inner face of the margin of the upper, or both to that face and to the upper face of the outturned flange of the lining. A short toe stiffener rendered properly soft is laid on the formed toe portion of the lining in such manner that the lower edge of the stiffener abuts the outturned flange of the lining. The toe portion of the upper is laid down over the toe stiffener and the shoe is again presented to the toe-forming machine to form the toe portion of the upper and to impart to the stiffener its desired shape, the outturned flange of the upper being stuck to the outturned flange of the lining. The shoe then goes to the stitchdown lasting machine; and thereafter the welt 129 and outsole 131 may be attached by the usual stitches 133.

In cheaper types of two-sole shoes, the separate toe forming of the lining may be dispensed with, and the short toe stiffener may be placed with its lower edge at a predetermined distance from the edge of the lining so that, after the toe portion of the lining and the upper, together with the toe stiffener, have been formed at a single operation, the lower edge of the toe stiffener will abut the outturned edge of the lining.

It will be noted that in both kinds of shoes which have been shown, the outturned flange of the upper is temporarily fastened directly or indirectly to the margin of the extension innersole, and that the toe stiffener having no outturned flange is located substantially entirely within the stitches which permanently fasten the outturned flange of the upper to the extension innersole. The term "short toe stiffener" as used in the appended claims designates a toe stiffener which has no outturned flange and may be located inside of the stitches referred to above and inside of the crease at the junction of the outturned flange of the upper with the body portion of the upper.

Having described my invention, what I claim as new and desire to secure by Letters Patent of the United States is:

1. The method of making a stitchdown shoe which comprises mounting an assembled upper together with an extension innersole upon a last, inserting a short toe stiffener, simultaneously shaping the toe stiffener and the toe portion of the upper, including forming a portion of said upper but not of said stiffener with an outturned flange, causing said flange to be fastened temporarily to the extended margin of the extension innersole so as to maintain the shape imparted to the toe stiffener, and thereafter lasting the shoe and permanently fastening said outturned flange to said innersole.

2. The method of making a stitchdown shoe which comprises mounting an assembled upper together with an extension innersole upon a last, inserting a short toe stiffener, simultaneously shaping the toe stiffener and the toe portion of the upper, including forming a portion of said upper but not of said stiffener with an outturned flange, causing said flange to be fastened temporarily to the extended margin of the extension innersole by means of cement so as to maintain the shape imparted to the toe stiffener and thereafter lasting the shoe and permanently fastening said outturned flange to said innersole.

3. The method of making a stitchdown shoe which comprises applying thermoplastic cement to the toe portion of an extension innersole and permitting the cement to harden, mounting an

assembled upper and the extension innersole upon a last, treating a toe stiffener with a liquid to soften it, inserting the stiffener between the lining and the upper, heating the cement to soften it, shaping the toe stiffener and the toe portion of the upper including forming a portion of said upper but not of said stiffener with an outturned flange, pressing the flange against the cement on the extension innersole so as to maintain the shape imparted to the stiffener, and thereafter permanently fastening said flange to said innersole.

4. The method of making a stitchdown shoe which comprises applying thermoplastic cement to the toe portion of an extension innersole and permitting the cement to harden, mounting an assembled upper and the extension innersole upon a last, treating a toe stiffener containing or consisting of a stiffening substance with a solvent for said substance, inserting the stiffener between the lining and the upper, heating the cement to soften it, shaping the toe stiffener and the toe portion of the upper including forming a portion of said upper but not of said stiffener with an outturned flange, pressing the flange against the cement on the extension innersole so as to maintain the shape imparted to the stiffener, and thereafter permanently fastening said flange to said innersole.

5. The method of making a stitchdown shoe which comprises applying thermoplastic cement to the toe portion of an extension innersole and permitting the cement to harden, mounting an assembled upper together with an insole upon a last, lasting the lining over upon the under side of the insole, tacking the extension innersole to the last, inserting a stiffener between the lining and the upper, heating the thermoplastic cement to soften it, shaping the stiffener and the toe portion of the upper including forming a portion of said upper but not of said stiffener with an outturned flange, pressing the flange against the cement on the extension innersole to fasten the flange temporarily to the innersole, and thereafter permanently fastening said flange to said extension innersole.

6. The method of making a stitchdown shoe which comprises mounting upon a last an assembled upper and an extension innersole the margin of the toe portion of which is coated with cement, shaping the toe portion of the lining in-

cluding forming a portion of said lining into an outturned flange, pressing said outturned flange against the cement on the extension innersole, placing a toe stiffener on the lining, shaping the toe stiffener and the toe portion of the upper including forming a portion of said upper but not of said stiffener with an outturned flange, pressing this flange against the flange of the lining, providing cement between the flanges so that they will adhere, and thereafter permanently fastening the two flanges to the extension innersole.

7. The method of making a stitchdown shoe which comprises mounting upon a last an assembled upper and an extension innersole the margin of the toe portion of which is coated with cement, inserting a toe stiffener between the upper and the lining, shaping the toe stiffener and the toe portion of the upper and the lining including forming outturned flanges on said upper and lining but not on said stiffener, pressing said outturned flanges and the margin of said extension innersole together, providing cement between the flanges so that the flanges will adhere together and to the innersole, and thereafter permanently fastening the two flanges to the extension innersole.

8. A stitchdown shoe comprising a lining and an upper both of which have outturned flanges, a toe stiffener between the upper and the lining, the lower edge of said stiffener substantially abutting the outturned flange of the lining and having itself no outturned flange, an extension innersole, and stitches located outside the toe stiffener and passing through the bases of the outturned flanges of the upper and lining and through the extension innersole.

9. A stitchdown shoe comprising a lining and an upper both of which have outturned flanges, a toe stiffener between the upper and the lining, the lower edge of said stiffener substantially abutting the outturned flange of the lining and having itself no outturned flange, an extension innersole, an outersole, stitches located outside the toe stiffener and passing through the bases of the outturned flanges of the upper and lining and through the extension innersole, and other stitches passing through the said outturned flanges, through the extension innersole and through the outersole.

ECKARD F. SCHMIDT.
